UNITED STATES PATENT OFFICE.

J WESLEY OHL, OF NILES, OHIO.

SLIDING-DOOR HANGER.

No. 927,272.

Specification of Letters Patent.

Patented July 6, 1909.

Application filed April 4, 1908. Serial No. 425,222.

To all whom it may concern:

Be it known that I, J WESLEY OHL, a citizen of the United States, residing at Niles, in the county of Trumbull and State of Ohio, 5 have invented new and useful Improvements in Sliding-Door Hangers, of which the following is a specification.

This invention relates to sliding door hangers, and is preferably constructed for use 10 upon sliding doors on cars of any description.

The object of the invention is to provide a sliding door hanger with a sheave frame which is readily adjustable upon the hanger so as to properly position the door in its relation to the floor and track upon which it is 15 supported.

Another object of the invention is to provide a device of this character having a hanger provided with a substantial housing 20 adapted for the reception of the sheave frame and sheave, the housing of the hanger being so constructed as to provide for the ready insertion of or removal of the sheave frame.

With these and other objects in view the invention resides in the novel construction of the elements comprising the hanger and their arrangement in operative combination, hereinafter fully described and claimed.

In the accompanying drawings, Figure 1 is a vertical sectional view through a door and door hanger provided with my improvements. Fig. 2 is a horizontal sectional view upon the line 2—2 of Fig. 1. Fig. 3 is a perspective 35 view of the sheave frame.

In the accompanying drawings the numeral 1 designates a movable door of that class usually employed upon cars of any ordinary construction, and the numeral 2 designates a track upon which the door 1 is 40 adapted to be moved.

The numeral 3 designates the hanger member of the improved device. As clearly illustrated in Fig. 2 of the drawings the member 45 3 is provided with an elongated face plate 4 provided with suitable openings adapted for the reception of securing devices 5, by which it is secured to the door 1, and also having its outer edge provided with an offset 6 adapted 50 for engagement with a transverse slot or recess formed in the side of the door 1, and by which the door is more securely supported by the member 4. The member 4 is extended a suitable distance beyond the top of the 55 door 1 and is provided with an offset or head 7. This head 7 is provided with a depending

member 8, spaced laterally away from the upper portion of the member 3 to provide a substantial housing 9 for a sheave frame, hereinafter to be described. The edges of 60 the parts comprising the housing 9 are each inturned to provide vertical ribs 10 whereby lateral movement of the sheave frame is effectively prevented.

The sheave frame 11 is preferably constructed of a single strip of metal, as illustrated in the figures of the drawing and comprises a front face 12 provided with a centrally arranged squared opening 13 and being bent rearwardly to provide a back face 14 65 parallel with the face 12 and having its lower end bent outwardly in the direction of the face 12 as designated by the numeral 15. The rear face of the sheave frame 11 is provided with a circular or round opening 16 aligning 70 with the squared opening 13 provided in the face 12 of the sheave frame. These openings 13 and 16 are adapted for the reception of an axle 18 seated in a bushing or hub 19 on which the sheave or wheel 20 is rotatably 75 mounted. This axle 18 has a squared body portion adapted to be seated in a squared central opening in the bushing 19 and the squared opening 13 upon the face of the sheave frame 12, while the opposite end of 80 the axle 18 is reduced and provided with a round portion adapted to engage the circular opening 16 provided in the face 14 of the sheave frame.

The head portion 7 of the hanger member 90 3 is provided with a centrally arranged vertical threaded opening 17, adapted for the reception of an adjusting screw 18' having its head provided with a squared wrench hold 19' by which the screw may be readily 95 rotated, and the lower face of the screw 18' is rounded as at 20' and adapted to be received in a depression 21 in the head of the sheave frame 11. By this arrangement, it will be seen that by simply rotating the 100 screw member 18' the sheave 20 carried by the sheave frame 11 may be pressed upon the track 2 so as to elevate the door 1 to the desired height. It will be also seen that the offset or projection 15 provided upon the 105 sheave frame 11 will contact with the under face of the track 2 when the door is attempted to be raised from either of its ends.

While I have shown and described the principal embodiment of my invention as it 110 now appears to me, it is to be understood that minor details of construction within the

scope of the following claims may be resorted to without departing from the spirit or sacrificing any of the advantages of the invention.

Having thus fully described the invention 5 what is claimed as new is:

In a hanger for sliding doors, the combination with a plate secured to the door, said plate being provided with an inverted U-shaped extended portion having its edges inverted to provide guide lugs, an inverted U-shaped sheave frame carrying a sheave or

wheel positioned within the inverted U-shaped projecting portion of the face plates, and means for adjusting the sheave frame upon the face plate. 15

In testimony whereof I affix my signature in presence of two witnesses.

J WESLEY OHL.
